UNITED STATES PATENT OFFICE

155,430

DESIGN FOR A BELT OR SIMILAR ARTICLE

Kenneth Krasnow, New York, N. Y., assignor to Krasnow Belt Co., Inc., New York, N. Y.

Application March 20, 1948, Serial No. 145,252

Term of patent 3½ years

(Cl. D3—10)

To all whom it may concern:

Be it known that I, Kenneth Krasnow, a citizen of the United States of America, residing at New York, county of Bronx, and State of New York, have invented a new, original, and ornamental Design for a Belt or Similar Article, of which the following is a specification, reference being had to the accompanying drawing, forming a part thereof.

Fig. 1 is a plan view of a belt showing my new design. The dot-and-dash lines indicate a design unit which is repeated throughout the length of the belt.

Fig. 2 is an edge view thereof.

I claim:

The ornamental design for a belt or similar article, as shown and described.

KENNETH KRASNOW.
